[57] CLAIM

The ornamental design for a radial aeroplane, as shown
and described.

DESCRIPTION

FIG. 1 is a top and front perspective view of a radial
aeroplane showing my new design.

FIG. 2 is a top plan view thereof.

FIG. 3 is a side elevational view thereof, the opposite
side elevational view being a mirror image of that
shown.

FIG. 4 is a bottom plan view thereof.

FIG. 1

FIG. 2

FIG. 3

FIG. 4
